BALL TOY WITH ACTION ELEMENT

Willis M. Lakin, Barton, Wis., assignor to Marlin Toy Products, Inc., Horicon, Wis., a corporation of Illinois

Filed Nov. 30, 1960, Ser. No. 63,029

Term of patent 14 years

(Cl. D34—15)

Figs. 1 and 2 are obverse perspective views of a ball toy with action element showing my new design;

Fig. 3 is a top view of the same;

Fig. 4 is a magnified fragment of the same showing parts of the action element as seen in the direction of lines 4—4 of Fig. 3.

I claim:

The ornamental design for a ball toy with action element, as shown.
